UNITED STATES PATENT OFFICE.

WILLIAM P. TALBOT, OF BROOKLYN, NEW YORK.

DESIGN FOR A WATCH GUARD.

Application filed June 26, 1926. Serial No. 18,194. Term of patent 3½ years.

To all whom it may concern:

Be it known that I, WILLIAM P. TALBOT, a citizen of the United States of America, residing at Brooklyn, Kings County, State of New York, have invented a new, original, and ornamental Design for a Watch Guard, of which the following is a specification, reference being had to the accompanying drawing, forming part hereof, in which—

Fig. 1 is a face view of a watch guard showing my new design and Fig. 2 is an end view thereof.

I claim—

The ornamental design for a watch guard as shown.

Signed at New York city, this 25 day of June, 1926.

WILLIAM P. TALBOT.
